(57) **CLAIM**

I claim the ornamental design for a set of attachments for an article of protective sports gear, as shown and described.

DESCRIPTION

FIG. 1 is a perspective view of a right-hand attachment of a set of attachments for an article of protective sports gear, showing my new design;

FIG. 2 is a side elevation view of FIG. 1;

FIG. 3 is a side elevation view of the opposite side of FIG. 2;

FIG. 4 is a front elevation view of FIG. 1;

FIG. 5 is a rear elevation view of FIG. 1;

FIG. 6 is a top plan view of FIG. 1;

FIG. 7 is a perspective view of a left-hand attachment of a set of attachments for an article of protective sports gear;

FIG. 8 is a side elevation view of FIG. 7;

FIG. 9 is a side elevation view of the opposite side of FIG. 8;

FIG. 10 is a front elevation view of FIG. 7;

FIG. 11 is a rear elevation view of FIG. 7;

FIG. 12 is a top plan view of FIG. 7;

FIG. 13 is a perspective view of a right-hand attachment of a second embodiment thereof;

FIG. 14 is a side elevation view of FIG. 13;

FIG. 15 is a side elevation view of the opposite side of FIG. 14;

FIG. 16 is a front elevation view of FIG. 13;

FIG. 17 is a rear elevation view of FIG. 13;

FIG. 18 is a top plan view of FIG. 13;

FIG. 19 is a perspective view of a left-hand attachment of a second embodiment thereof;

FIG. 20 is a side elevation view of FIG. 19;

FIG. 21 is a side elevation view of the opposite side of FIG. 20;

FIG. 22 is a front elevation view of FIG. 19;

FIG. 23 is a rear elevation view of FIG. 19; and,

FIG. 24 is a top plan view of FIG. 19.

The details shown in broken lines are for illustrative purposes only and form no part of the claimed design.
